ABSTRACT OF THE DISCLOSURE

An inflatable undersea structure having a natural configuration when submerged and including load tapes for countering uniaxial stresses. The gas filled structure when submerged creates a buoyant force which is transformed into only uniaxial stress at the wall of the natural shape envelope with no circumferential stress. Load tapes sustain the uniaxial forces and relieve the structure of substantially all stress thus permitting the device to be constructed of relatively weak or transparent materials.

The invention described herein may be manufactured and used by or for the Government of the United States of America for governmental purposes without the payment of any royalties thereon or therefor.

BACKGROUND OF THE INVENTION

Field of the invention

This invention relates in general to undersea structures such as chambers which may be inflatable to provide a protected underwater storage or living space.

Description of the prior art

Previously underwater containers have been of spheroidal or cylindrical configuration which shapes induce biaxial or multiaxial stresses in the wall of the structure. Accordingly it has been necessary to make such prior structures of heavy, high strength material precluding the use of lightweight, transparent materials. There is nothing in the prior art concerned with the problem solved by the present invention, namely to provide an underwater structure possessing a rotationally symmetrical configuration about a vertical axis thus permitting the structure to be manufactured from a flexible, lightweight transparent material of relatively low strength.

SUMMARY

Briefly stated, the present invention in general contemplates an undersea chamber or housing suitable as a storage or inhabitable observation means. The device includes an inflatable undersea structure of flexible material which assumes a natural configuration upon which only uniaxial stress forces are imposed, the latter being opposed by means of load tapes. Thus, with the meridional stress substantially reduced and with no circumferential stress involved; a structure may be made of lightweight, transparent material which assumes and retains a natural shape because of gas under ambient pressure within the structure.

Accordingly it is an object of this invention to provide a submerged inflatable structure with wall or membrane stresses oriented meridionally with zero circumferential stress so that lightweight transparent materials may be employed on the structure wall to increase visibility and buoyancy.

2

Another object of the invention is to provide a submerged ambient pressure natural shaped gas envelope with the sole meridional wall stress generated by the buoyancy of the gas volume within the envelope relieved by load tapes incorporated into the wall.

A further object of the invention is to provide a submerged ambient pressure natural shaped gas envelope having thin and transparent wall membranes.

Other objects, advantages, and novel features of the invention will become apparent from the following detailed description of the invention when considered in conjunction with the accompanying drawings.

BRIEF DESCRIPTION OF THE DRAWINGS

15 FIGURE 1 is a vertical cross section of the present invention when submerged.

FIGURE 2 is a view in perspective of the present invention showing the multiple load tapes.

DESCRIPTION OF THE PREFERRED EMBODIMENT

Referring now to the drawings in detail there is shown in FIG. 1 the submerged envelope indicated generally as 10 with the inflated flexible wall 12 assuming the configuration or shape that would be natural in submerged conditions. The inflated structure is free of circumferential stress when submerged and its buoyant force shown figuratively as 14 is restrained at the perimeter by vertical forces 16.

30 The natural configuration of the envelope 10 referred to previously depends on the density ratio of water to air or any other gas or combination of gases such as a helium-oxygen mixture that may be used within the envelope 10. By allowing the gas filled envelope to assume its natural submerged shape, the structure possesses a rotationally symmetrical configuration and is free of circumferential or later stress with only meridional or uniaxial stress remaining in the wall 12.

35 In order to counteract the meridional stress the uniformly spaced load tapes 18 are incorporated into the wall 12 thereby reducing the aforesaid meridional stress to substantially zero. This permits the inflatable envelope 10 to be constructed of relatively low strength and transparent materials having excellent visibility or high buoyancy characteristics.

40 45 It is pointed out that a natural configuration will be obtained if a fluid other than gas is employed to inflate the submerged envelope 10. Such fluid may be gasoline or oil, etc. However, a suitable density ratio of water to fluid must always be maintained.

50 Thus it is clear that the structure of the present invention will show increased visibility and ease in handling. Furthermore, it is easily fabricated at low cost.

55 Obviously many modifications and variations of the present invention are possible in the light of the above teachings. It is therefore to be understood that within the scope of the appended claims the invention may be practiced otherwise than as specifically described.

What is claimed is:

1. An undersea walled structure comprising:
an inflatable envelope filled with a gas and possessing a natural configuration when submerged so that forces acting on the envelope are transformed into a single uniaxial stress; and
means incorporated into said envelope to counteract said uniaxial stress acting on said envelope, thus relieving the walls of said envelope substantially free of said stress.

2. An undersea structure as defined in claim 1 wherein the means incorporated into said envelope to counteract the uniaxial forces includes uniformly spaced load tapes.

3. An undersea structure as defined in claim 1 wherein said envelope is constructed of a lightweight, membrane material having transparent characteristics.

4. An undersea structure as defined in claim 1 wherein in said gas is life sustaining.

5. An undersea structure as defined in claim 4 wherein said life sustaining gas comprises a helium-oxygen mixture.

6. An undersea structure as defined in claim 1 wherein a fluid other than a gas is employed to fill said inflatable envelope.
